UNITED STATES PATENT OFFICE

JOHN E. ANDERSON, OF BOILING SPRINGS, PENNSYLVANIA.

IMPROVEMENT IN WASHING-MACHINES.

Specification forming part of Letters Patent No. **139,992**, dated June 17, 1873; application filed March 12, 1873.

To all whom it may concern:

Be it known that I, JOHN E. ANDERSON, residing in Boiling Springs, in the county of Cumberland and State of Pennsylvania, have invented a new and useful Improvement in Washing-Machines, of which the following is a full, clear, and exact description, reference being had to the annexed drawing, in which—

Figure 1 is a plan view, and Fig. 2 a longitudinal vertical section, of my improved washing-machine.

Corresponding letters are used in the designation of corresponding parts in both figures.

The nature of this invention consists of combining with a shoe or rubber, having a single or compound rubbing-surface, a water-feeding device, composed of an inclined board or strip hinged or otherwise attached to vertical bars secured to the inner sides of the rubber; and, further, of the combination of the above elements with one or more pivoted or yielding rubbers, disposed in the end or ends of the containing-vessel, substantially as hereinafter more fully set forth.

To enable others to make and use my invention, I will proceed to describe it.

The containing-vessel A, which is preferably of an oblong or rectangular shape, and mounted upon suitable legs, is supplied in its sides near the upper edges of the latter with elongated slots *a*, the office of which will be referred to hereinafter. The shifting shoe B, in the present instance, is constructed with a compound or double-concave rubbing-surface, consisting of two series of stationary rolls or bars, slightly separated for the passage of water between them, and adjusted to and between two uprights or boards, so as to conform to the concave or curved surfaces with which the said boards are supplied, and standing back to back, as shown in the drawing. This construction enables two distinct washings to be performed at once; consequently, if the shoe has simply a single concave rubbing-surface, the object of my invention will still be carried out. The rolls are held separated from one another by metallic rings, embracing them, and the boards which receive the said rolls are supplied upon the lower edges with flat springs or frictional rollers. C C refer to

the device for feeding or supplying the water to the rubbing-surfaces of the shifting shoe as it is passed back and forth, and it is composed of two uprights, suitably attached to the inner sides of the boards of the shoe, but not reaching down to the lower edges thereof, and of two boards, or of one when only one rubbing-surface is imparted to the shoe, which are set in an inclined position and fastened or hinged or pivoted to the correspondingly-shaped surfaces or edges of the said uprights. (See Fig. 2.)

It will be here observed that the other advantages arising from this construction of the shifting shoe are, the length of its pitch and of its rubbing-surfaces can be increased, and the containing-vessel be of the shortest size possible wherein the amount of water to be used can be lessened.

To the top of the shoe B is fitted a cap or board, *b*, passing through the elongated slots *a* of the containing-vessel, and receiving the hooked ends of the pitmen D, suitably connected to levers or handles D' D', fastened to an axis having its bearings in appendages attached to the said vessel, or pivoted upon an axis fastened to the vessel, as in the drawing. Through this mechanism the shoe is worked, or shifted back and forth to perform the washing of the articles. E E refer to two other rubbing devices, one hinged or pivoted in one end of the containing-vessel, and the other in the opposite end thereof, and consisting of frames, whose front portions are supplied with a series of angular bars or slats to assist in rubbing the articles to be washed, and the lower portions, with beveled surfaces, enveloped or encircled by some anti-frictional material, and which run upon the shifting shoe as it moves back and forth, so as to assist the latter in the performance of its work. Adjusted to the lower side of the vessel A, beneath an opening cut in the bottom thereof, is a trough or receptacle, F, with a discharge-orifice, and for the purpose of receiving or conducting the sediments, dirt, &c., from the vessel.

Other receptacles are fastened to the ends of the vessel A.

Having thus fully described my invention,

what I claim, and desire to secure by Letters Patent, is—

1. In combination with the rubber or shoe B, with one or more rubbing-surfaces, the water-feeding device C C, composed of inclined boards or strips, preferably hinged to vertical bars secured to the inner sides of the rubber, substantially as shown and set forth.

2. The combination of the elements of the above claim with the pivoted or yielding rub-

ber or rubbers E E, substantially as and for the purpose set forth.

In testimony whereof I have hereunto signed my name this 28th day of February, 1873, in presence of two subscribing witnesses.

JOHN E. ANDERSON.
